United States Patent Office.

WILLIAM A. LIGHTHALL, OF NEW YORK, N. Y.

Letters Patent No. 89,156, dated April 20, 1869

IMPROVEMENT IN STEAM-ENGINEERING FOR SURFACE-CONDENSERS.

The Schedule referred to in these Letters Patent and making part of the same.

To all whom it may concern:

Be it known that I, WILLIAM A. LIGHTHALL, of the city, county, and State of New York, have invented certain new and useful Improvements relating to Surface-Condensers for Steam-Engines; and I do hereby declare that the following is a full and perfect description of the same, reference being had to the accompanying drawings, and to the letters of reference marked thereon, in which—

Figure 1 is a plan view, and

Figure 2, a side elevation.

It is found in practice, that the circulating-pump, to furnish cooling-water to the surface-condenser of a steam-engine, should, primarily, be independent of the movement of the engine to which the surface-condenser is attached, so that it can operate when the main engine is not in motion.

It is also found in practice, that the "air-pump" ordinarily used, is greatly increased in capacity beyond the absolute requirement.

It is also found in practice that these objects can be gained by a much less loss of power, which constitutes the purpose and effect of my invention.

I effect these purposes by the use of an independent driving-engine, which operates, both the circulating-pump, to furnish cooling-water to the surface-condenser, and also the "air-pump," to take from the condenser the incondensable vapor that cannot be condensed in the surface-condenser.

It is, therefore, nearly automatic in its operation, as the greater the pressure of steam, so is, relatively, the greater number of revolutions of the pump for cooling-water, and of the air-pump for removing from the condenser the incondensable vapor.

Referring to the drawings hereto attached,

A is an independent engine, which drives both the circulating-pump and the air-pump.

It is so connected with the condenser, that it is almost entirely operated by reason of the vacuum in the condenser, avoiding, thereby, the use of much less "live steam" to operate it than that heretofore necessary.

B is the circulating-pump, to furnish the supply of cooling-water to the surface-condenser, through the proper pipes and attachments.

C is the "air-pump," which is attached to and driven by the shaft of the engine A, to effect its purpose named.

The surface-condenser, to which I intend to attach this arrangement, is not shown in the drawings, but it will be apparent that the combination and arrangement will fully answer for any condenser of the surface-class now made and used.

I know that the combination of the driving-engine, circulating-pump, and air-pump, has been heretofore used; but in all such cases they have been driven together by the main engine. I therefore disclaim such arrangement, and only claim the arrangement of the independent engine, with the other devices pertaining thereto, the benefit of which will be apparent to practical engineers.

What I claim as my invention, and desire to secure by Letters Patent, is—

The arrangement of the driving-engine A, circulating-pump B, and air-pump C, when all co-operate together, to perform the functions herein set forth.

WM. A. LIGHTHALL.
